UNITED STATES PATENT OFFICE.

ROBERT W. BOSTWICK AND GRANT W. BOSTWICK, OF DETROIT, MICHIGAN.

WINDOW REGULATOR.

Application filed October 3, 1924. Serial No. 741,453.

To all whom it may concern:

Be it known that we, ROBERT W. BOSTWICK and GRANT W. BOSTWICK, citizens of the United States of America, residing at 5 Detroit, in the county of Wayne and State of Michigan, have invented certain new and useful Improvements in Window Regulators, of which the following is a specification, reference being had therein to the accompanying drawings.

The invention relates to window regulators designed particularly for use in vehicles and has for one of its objects the provision of improved means for holding the 15 handle upon the shaft and for holding the member, for raising and lowering the window, from movement in either of its directions. Another object is to provide a structure which is compact and may be cheaply 20 manufactured.

Further objects of the invention reside in the novel features of construction and combinations and arrangements of parts as more fully hereinafter set forth.

25 In the drawings:

Figure 1 is an inside elevation, partly broken away, of a portion of a vehicle with the window regulator embodying my invention applied;

30 Figure 2 is a cross section on the line 2—2 of Figure 1;

Figure 3 is a cross section;

Figure 4 is a perspective view of portions of the handle and handle shaft and the 35 washer therebetween shown separated.

1 is the mounting plate for the window regulator secured in the present instance to the lock board 2 of a motor vehicle door. 3 is the lifter arm pivotally mounted at 4 upon the mounting plate and suitably connected at its free end to the window. This lifter arm preferably has the integral gear segment 5 at its pivot end, the teeth of which mesh with the teeth of the gear 6. 40 This gear is actuated by means of the handle shaft 7 and handle 8, the latter being located at the inner side of the door.

To hold the gear 6 in its adjusted positions of rotation thereby holding the lifter arm and window in their adjusted positions, I have provided a positive lock which is controlled by the handle 8. In detail, the lock comprises the ratchet wheel 9 the teeth of which are engageable by corresponding 55 ends of the pawls 10 and 11, the opposite ends of which are pivotally connected at 13

and 14 respectively to the disc 12. This disc 12 is nonrotatably secured upon the gear shaft 15, the inner end of which is journaled axially in the handle shaft 7 and between the pawls 10 and 11. The handle shaft is provided with the transverse projections 16 upon diametrically opposite sides of its axis and preferably in the nature of pins, for engagement with the cam surfaces 17 upon the pawls 10 and 11. These cam surfaces are in the nature of semi-circular recesses formed in the outer edges of the pawls between their ends. The arrangement is such that upon rotation of the handle in either direction the transverse projections upon the handle shaft ride over the cam surfaces upon the pawls to swing these pawls toward the axis of the handle shaft thereby simultaneously releasing the same from the ratchet wheel. When both of the pawls have reached the limit of their swinging movement the disc will then be rotated through the pawls and their pivots thereby rotating the gear and consequently the lifter arm and actuating the window.

For the purpose of normally holding the pawls in engagement with the ratchet wheel there is the U-shaped spring 18 extending around the gear shaft 15 and engaging the adjacent faces of the pawls 10 and 11. For limiting the swinging of the pawls toward the axis of the handle shaft during their releasing movement, these pawls have the transverse projections 19 extending toward 80 and engageable with each other.

The mounting plate 1 has the annular inwardly offset embossed portion 20 to the inner face of which the ratchet wheel 9 is secured by suitable means such as the rivets 21. This embossed portion is concentric with the axis of the pinion shaft to accurately locate the disc 12.

To hold the handle 8 upon the handle shaft 7 the inner end portion 22 of the handle shaft is reduced and threadedly engages in the handle. The adjacent surfaces of the handle shaft and handle are provided with the pairs of shoulders 23 and 24, the shoulders of each pair being preferably diametrically opposite each other and the shoulders of the handle shaft facing oppositely to the shoulders of the handle and preferably extending at right angles thereto. The adjacent surfaces of the handle shaft and handle between their respective shoulders are inclined. 25 is a spring washer between the

adjacent surfaces of the handle shaft and handle and surrounding the reduced end portion 22 of the handle shaft. This spring washer has struck-out therefrom the pairs 5 of oppositely facing projections or tongues 26 and 27, one pair being at right angles to the other pair and the projections of each pair being diametrically opposite each other. The projections 26 are struck inwardly to 10 engage the shoulders 23 of the handle shaft while the projections 27 are struck outwardly to engage the shoulders 24 of the handle. The arrangement is such that the handle may be screwed upon the handle 15 shaft during which time its inclined surface adjacent to the surface upon the handle shaft will ride over the projections 27 until the handle has been firmly tightened upon the handle shaft. If it is attempted to unscrew the handle from the handle shaft the 20 projections 27 of the spring washer coming into engagement with the shoulders 24 of the handle prevent the unscrewing. As a consequence the handle is firmly secured 25 upon the handle shaft and will rotate the same in either direction.

What we claim as our invention is:

1. In a window regulator, the combination with a member rotatable in opposite 30 directions for raising and lowering a window, of a stationary member provided with teeth, a plurality of members connected to said rotatable member and engageable with the teeth of said stationary member to hold 35 said movable member on opposite sides of its axis from rotation in either direction, and means for releasing said holding members and subsequently rotating said rotatable member in either direction.
- 40 2. In a window regulator, the combination with a member rotatable in opposite directions for raising and lowering a window, of a stationary ratchet wheel, pawls connected to said rotatable member and engageable 45 with the teeth of said ratchet wheel on opposite sides of its axis to hold said rotatable member from rotation in either direction, and means for releasing said pawls from said ratchet wheel and subsequently rotating 50 said rotatable member.
3. In a window regulator, the combination with a gear rotatable in opposite directions for raising and lowering a window, of a stationary ratchet wheel, a pair of 55 pawls connected to said gear, and engageable with the teeth of said ratchet wheel on opposite sides of its axis, and an operating member for releasing both of said pawls from said ratchet wheel and rotating said 60 gear in either direction through one of said pawls.

4. In a window regulator, the combination with a gear rotatable in opposite directions for raising and lowering a window, of a stationary ratchet wheel, a disc between said ratchet wheel and gear and connected to the latter, pivoted pawls upon said disc and engageable with the teeth of said ratchet wheel to hold said gear from rotation in either direction, means for yieldably forcing said pawls into engagement with the teeth and an operating member provided with means engageable with said pawls to release the same from said ratchet wheel and subsequently rotate said disc in either direction through one of said pawls.

5. In a window regulator, the combination with a gear rotatable in opposite directions for raising and lowering a window, of a ratchet wheel, a disc adjacent to said ratchet wheel and connected to said gear, a pair of pawls pivotally connected at corresponding ends to said disc and having the opposite ends engageable with the teeth of said ratchet wheel to hold said disc and gear from rotation in either direction, said pawls having cam portions and an operating member provided with members engageable with said cam portions to initially release said pawls from said ratchet wheel and subsequently rotate said disc and gear.

6. The combination with a member rotatable in opposite directions for raising and lowering the window, of a stationary ratchet wheel, a pawl connected to said rotatable member and engageable with the teeth of said ratchet wheel to hold said rotatable member from rotation, a rotatable driving member and means upon said rotatable driving member and having a cam action upon said pawl for releasing the same from said ratchet wheel and for subsequently rotating said rotatable member through said pawl.

7. In a window regulator, the combination with a gear rotatable in opposite directions for raising and lowering a window, of a stationary ratchet wheel, a pair of pawls connected to said gear and engageable with said ratchet wheel, opposed projections on said pawls engageable to limit movement thereof in one direction, an operating member, and means on said operating member for moving said pawls from engagement with said ratchet wheel into abutting position, whereby a rigid connection is established between said operating member and gear for rotating the latter.

In testimony whereof we affix our signatures.

ROBERT W. BOSTWICK.
GRANT W. BOSTWICK.
